DESIGN FOR A DRESS

Joset Walker, New York, N. Y.

Application November 6, 1941, Serial No. 104,040

Term of patent 3½ years

To all whom it may concern:

Be it known that I, Joset Walker, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of the dress shown in Fig. 1.

Fig. 3 is an enlarged fragmentary open side view of the dress shown in Fig. 1.

The characteristic feature of my design resides in the combination on the specific dress disclosed of the diagonally closing fly-type front opening having clip type closures arranged along the fly seam as shown.

I claim:

The ornamental design for a dress, substantially as shown and described.

JOSET WALKER.
